UNITED STATES PATENT OFFICE.

CALEB LIDDICOAT, OF ALBIA, IOWA.

CAR BRAKE OR STOP.

1,399,972.

Specification of Letters Patent. Patented Dec. 13, 1921.

Application filed February 11, 1920. Serial No. 357,801.

To all whom it may concern:

Be it known that I, CALEB LIDDICOAT, a citizen of the United States, residing at Albia, in the county of Monroe and State of Iowa, have invented certain new and useful Improvements in Car Brakes or Stops, of which the following is a specification, reference being had to the accompanying drawings.

10 This invention relates to car stops or "car spraggers" as they are known in mining parlance, and the general object of the invention is the provision of a device of this character adapted to engage and hold one or more cars, or for the purpose of slowing up moving cars in mines and on tramways.

20 A further object is to provide a device of this character which may be operated with perfect safety to the operator, and in which the actuating mechanism may be located any desired distance from the stop or brake.

25 And another object is to provide a device of this character embodying a longitudinally extending rail upon which the car wheels run and a longitudinally extending braking rail disposed over the first named rail and having linked engagement therewith, weight operated means for urging the braking rail away from the first named rail, and manually operable means for shifting the braking rail toward the first named rail.

30 A further object is to provide a construction of this character in which the braking rail is urged away from the supporting rail by a weight operated lever having an eccentric at one end disposed to engage an elongated link or lever mounted on the braking rail, the weight being adjustable to any desired extent and normally urging the rails apart.

40 Other objects will appear in the course of the following description.

45 My invention is illustrated in the accompanying drawings, wherein:—

Figure 1 is a side elevation of a "spragger" or car braking mechanism constructed in accordance with my invention;

Fig. 2 is a section on the line 2—2 of Fig. 1;

50 Fig. 3 is an enlarged elevation of a portion of the braking mechanism, the brake actuating link being partly broken away.

55 Referring to these drawings, it will be seen that my improved braking device comprises stringers 10 which are laid upon the usual transverse ties 11, these stringers sup-

porting the rails 12, which are preferably angular in cross section, as illustrated in Fig. 2, to provide an outside, upwardly extending flange. The opposite rail 13 is of ordinary or usual form, and the upper face of the angular rail 12 is disposed in line with the upper face of the rail 13. Disposed above the rail 12 in parallel relation thereto is a braking rail 14, which is angular in cross section, and provided on its inner face with a shoe of friction material 15 which may be of wood, leather, or any other suitable material having a frictional surface adapted to engage the wheels A of the car or cars B. Each of these rails 12 and 14 is provided with outwardly extending pivot studs 16, perforated at their extremities for the passage of cotter pins. Connecting the rail 14 to the rail 12 at a plurality of points and engaging these pivot studs 16 are a plurality of links 17 which are, of course, parallel to each other. The braking rail 14 is extended at one end beyond the rail 12, as shown in Fig. 1, and pivotally connected to these two rails is an elongated controlling link 18 which is also disposed in parallel relation to the links 17. The upper end of this link is laterally deflected, as at 19, then upwardly extending 85 and has a longitudinally extending groove 20 formed on its inside face. Across this groove is disposed a pin 21 which preferably carries a roller or loose sleeve on it.

Extending upward at one side of the track 90 is a post 22 which is longitudinally slotted, as at 23, for the passage of the elongated link or arm 18, and pivoted to this post is a lever 24, the upper end beyond the pivot being formed as a loop 25. The upper portion of this loop is circular and the curvature of this upper portion is eccentric to the pivot 26 of the lever. This loop is disposed between the pin 21 and the bottom of the groove 20, as shown most clearly in Fig. 3. 100 Mounted upon the lever and slidably therealong is a weight 27 which is held in place by set screws 28. Also extending upwardly at the side of the track is a post 29 carrying a pulley 30 at its upper end, over which passes an operating cable 31, the lower end of which is attached to the extremity of the lever 24. This operating cable extends over one or more pulleys 30 mounted on posts 29, and then extends to an arm 31 operatively connected to a lever 32, which lever operates over a rack 33 provided with teeth, the lever

having a bolt 34 engageable with this rack and operated by a hand grip 35.

It will be obvious now that when it is desired to brake or slow down a car coming in the direction of the arrows in Fig. 1 or hold a car from movement, the lever 32 is drawn toward the left in Fig. 1, which draws upon the cable 31 and causes the cable to draw upward on the lever 24. The outer end of this lever operates, therefore, to depress the outer end of the arm of the actuating link 18, thus depressing the upper rail 14 so as to bring it in braking and frictional engagement with the car wheel A. The movement of the controlling link 18 under the action of the eccentric loop 25 is relatively small but the action is very strong. Thus it will be obvious that the braking rail may be shifted to a very slight amount if desired and thus cause either a gentle braking action on the car, or a relatively strong braking action which will either restrain the car from rapid movement or hold the car from any movement at all. It is obvious also that the controlling lever 32 might be disposed at any convenient point, either beside the track or considerably to one side of the track, and that the actuating cable may be run over suitable pulleys or guides to the controlling lever without regard to the position of the controlling lever with reference to the track.

In Fig. 1, I have illustrated two sets of upper and lower rails 12 and 14, both of these sets of rails being constructed like each other, but one set of controlling rails being connected to the other set of controlling rails by means of a longitudinally extending sectional rod 36, the sections of the rod being connected by means of a turn buckle 37 and the ends of the rod being pivoted to adjacent studs 16. It, therefore, is to be understood that there may be any number of sets of these brakes, all controlled from a single lever 32, and that these braking rails 12 and 14 may be of any desired length so as to control and brake either one car or a plurality of cars.

This car braking or stopping mechanism is designed for use in mines and for surface tramways or any other situation where it is desirable to reduce the speed of cars or stop them altogether. When the upper brake is lowered toward the lower rail, it is obvious that a very firm grip will be secured upon the wheels of the car and that by its means runaway cars in mines and outside tramways may be readily caught and slowed up. It will further be noted that this device will prevent runaway cars which are being slowed up from getting off the track, as there is no tendency for the cars to pile up on each other because the brake shoe is applied to all of the wheels of the cars, and further because the brake may be applied gradually. The angular form of the brake shoe,

when taken with the angular form of the supporting rail, holds the cars to the tracks and tends to prevent any lateral movement of the cars which would derail them.

Heretofore when it has been desired to hold mining cars from movement, it has been usual to insert a stick of wood between the spokes of the wheels. This is very dangerous where cars are moving and has caused many accidents and deaths.

My device is very simple, may be easily applied to any mining railway or tramway, and has been found thoroughly effective in practice. It will be seen that the particular form of lever used by me having the eccentric loop 25 exerts a great force upon the actuating arm 18, both to lift the braking rail or to depress it under the action of the cable 31. As soon as the lever 32 is released, the counterweight will cause the lever 24 to return to the position shown in Fig. 3 and thus lift the brake shoe from the wheels.

I claim:—

1. A braking device of the character described comprising a lower supporting rail, an upper braking rail, links pivotally connecting the two rails, a counterweight urging the braking rail away from the supporting rail, and manually operable means for shifting the braking rail toward the supporting rail and including an actuating arm pivotally connected to the supporting rail and the braking rail, and extending upward beyond the braking rail, a lever operatively connected to the upper end of said arm, a manually actuatable device, and connections leading from said last named lever to the actuating device whereby the lever may be shifted to cause the braking rail to move toward the supporting rail.

2. A braking mechanism of the character described comprising a supporting rail and braking rail, links pivotally connecting the braking rail to the supporting rail, one of said links being extended to form an actuating arm, a support, a lever pivoted in the support and operatively connected to the upper end of said actuating arm, a counterweight on said lever and urging the lever and arm to shift the rails apart and manually operated means for shifting the lever to shift said rails toward each other.

3. A braking mechanism of the character described comprising a supporting rail and braking rail, links pivotally connecting the braking rail to the supporting rail, one of said links being extended to form an actuating arm, a support, a lever pivoted in the support and operatively connected to the upper end of said actuating arm, a counterweight on said lever and urging the lever to shift the rails apart, and manually operated means for shifting the lever to shift said rails toward each other and including a cable extending from the counterweighted le-

ver and a lever to which the cable is operatively connected, said last named lever being adjustable to various positions.

4. A braking mechanism of the character described comprising a supporting rail and a braking rail, links pivotally connecting the braking rail to the supporting rail, an actuating arm pivotally connected to the supporting rail and the braking rail, a lever having an eccentric member operatively engaging one end of the actuating arm whereby the movement of the lever in one direction acts to depress one end of the actuating arm and in the other direction acts to raise the actuating arm, and manually operable means for shifting said lever.

5. A braking device of the character described comprising a supporting rail, angular in cross section, a braking rail disposed in approximately parallel relation to the first named rail and angular in cross section, links pivotally connecting the rails and permitting the braking rail to move toward and from the supporting rail, one of said links being elongated to form an actuating arm, a pivotally supported lever having one end operatively engaging the actuating arm and its other end counterweighted whereby to cause the lifting of the actuating arm and the lifting of the braking rail, manually operable means operatively connected to the free end of the lever to shift the lever against the action of the counterweight and depress the braking rail, said means including a lever operating over a rack, means for holding the lever in adjusted positions, and a flexible connection between the lever and the free end of the counterweighted lever.

40 6. A braking mechanism of the character described including a supporting rail, a braking rail disposed above the supporting rail, links pivotally connecting the two rails, one of said links being extended to form an actuating arm and being longitudinally recessed at its upper end, a pivotally supported lever having an eccentric loop at one end engaging in said recess, the opposite end of said lever being counterweighted, a pin 45 extending through the walls of said groove and extending through the loop of the eccen-

tric lever, and manually actuatable means for raising the counterweighted end of the lever against the force of the counterweight to thereby cause the movement of the braking 55 rail toward the supporting rail.

7. A braking mechanism of the character described comprising a supporting rail, angular in cross section, a braking rail disposed in alinement above the supporting 60 rail, and also angular in cross section, the lateral flanges of said rails extending toward each other and having outwardly projecting pivot studs, links connecting the rails and pivoted to the studs, one of said 65 links being upwardly extended and formed with a recess at its upper end, a post through which said extended link passes and by which it is guided, a pin extending across said recess, a lever pivotally mounted 70 upon the post and having an eccentric loop through which said pin passes, said loop having a uniformly curved, outer portion and having a thickness equal to the distance 75 between the pin and the bottom of the recess, an adjustable counterweight mounted upon the opposite end of the lever, a manually actuatable lever, a rack whereby it may be held in adjusted positions, and a flexible 80 connection extending from said manually 85 actuatable lever to the free end of the counterweighted lever.

8. In a mechanism of the character described, a track including a pair of rails, one of said rails including a supporting rail angular in cross section to provide an upwardly extending flange and an inwardly extending flange directed toward the opposite rail, a braking rail disposed in alinement above the supporting rail and also angular in cross section to provide a downwardly extending flange, and a flange extending toward the opposite rail, the vertical flanges of said rails having outwardly projecting pivot studs, links connecting the 90 rails and pivoted to the studs, means for urging said rails away from each other, and manually operable means for shifting the rails toward each other.

In testimony whereof I hereunto affix my 100 signature.

CALEB LIDDICOAT.
